BUILT-IN TOASTER AND WARMER COMBINATION

Edward D. Gidseg, 14 Cricket Lane, Kings Point,
Great Neck, N.Y. 11024

Filed Dec. 5, 1966, Ser. No. 4,915

Term of patent 14 years

(Cl. D81—10)

FIG. 1

FIG. 2

FIG. 1 is an exploded frontal perspective of the toaster and warmer combination embodying my design, with an upper removable panel shown in displaced position for access to the warmer part of the combination;

FIG. 2 is a front elevation thereof;

FIG. 3 is a side elevation thereof with the aforementioned upper panel displaced;

FIG. 4 is an upper plan view thereof with the aforementioned upper panel displaced;

FIG. 5 is a lower plan view of the embodiment of FIG. 1 with the aforementioned upper panel displaced; and

FIG. 6 is an elevation of the aforementioned upper panel as seen from the rearward side thereof.

The dominant features of my design reside in the portions shown in full lines.

I claim:

The ornamental design for a built-in toaster and warmer combination, as shown and described.
